UNITED STATES PATENT OFFICE.

THOMAS P. MADDEN, OF ST. LOUIS, MISSOURI.

LOCOMOTIVE ASH-PAN.

1,277,972.

Specification of Letters Patent. Patented Sept. 3, 1918.

Application filed December 8, 1917. Serial No. 206,224.

To all whom it may concern:

Be it known that I, THOMAS P. MADDEN, a citizen of the United States, residing at the city of St. Louis, State of Missouri, have 5 invented a certain new and useful Improvement in Locomotive Ash-Pans, of which the following is a full, clear, and exact description, such as will enable others skilled in the art to which it appertains to make and use 10 the same, reference being had to the accompanying drawings, forming part of this specification, in which,—

Figure 1 is a side elevational view of my improved locomotive ash pan.

Fig. 2 is an elevational view looking toward the front of the locomotive.

Fig. 3 is a cross sectional view of my improved ash pan.

Fig. 4 is a detail view of certain of the 20 parts of my improved ash pan before the same are pressed into shape.

This invention relates to a new and useful improvement in locomotive ash pans of the type shown and disclosed in my United 25 States Letters Patent No. 1,107,682 dated August 18, 1914, the object of my present invention being to simplify the invention and to cheapen the cost of manufacture.

As disclosed in my aforesaid patent, the 30 ashes from the grate bars drop into the ash box and are then flushed out by water under pressure. These principles I have proposed to follow in the present instance by providing a water head 1 in which water is 35 supplied from the tank, preferably under pressure, said water flushing the ashes down through the trough shaped bottom member of the ash box so that the same will be discharged through the door at the lower end 40 thereof.

In the drawings, 2 indicates a mud ring of the boiler under which are secured brackets 3. To these brackets 3 are secured the members 4 of the ash pan, these members being 45 provided with openings at proper intervals, which openings are covered by plates 4^a, the latter accommodating such driving wheels or parts of the engine frame which have an independent movement relative to said ash 50 pan. The plates 4 of the ash pan are preferably inclined downwardly and at their in-

ner edges are provided with flanges 4^b to which latter are secured the wall portions 5 of the rounded trough shaped member 6 of the ash pan. This rounded trough shaped 55 bottom member is preferably formed from a segmental piece of rolled sheet iron or steel, as shown in Fig. 4, and by its conformation, when curled up, it is made deeper 60 at one end than at the other. The deepest portion is covered by a door 7 which may be opened or closed by an operating rod 8 which may be reciprocated by the engineer by suitable connections.

While I have shown the vertical walls 5 65 and the hopper portion 6 of the ash pan as being made in one piece, it is obvious that they can be made in separate pieces and connected together.

The virtue of spacing the inclined walls of 70 the ash pan over the mud ring resides in the ability of the fireman to flush these walls with a hose to clean the same from ashes when the engine is "spotted", that is, in the roundhouse or over a pit.

It will be readily understood that minor 75 changes in the size, form and construction of the various parts of my improved locomotive ash pan may be made and substituted for those herein shown and described, without departing from the spirit of my invention, the scope of which is set forth in the appended claim.

I claim:

A locomotive ash pan comprising inclined 85 members spaced from the mud ring of the boiler, said members having flanges at their inner edges to which is secured a trough-shaped bottom member comprising a curled segmental element forming an inclined 90 curved bottom wall of variable depth which is open at its deepest end, in combination with a door for closing said opening, and means for operating said door.

In testimony whereof I hereunto affix my 95 signature in the presence of two witnesses, this fifth day of December, 1917.

T. P. MADDEN.

Witnesses:

M. P. SMITH,
M. A. HANDEL.
